(57) **CLAIM**

The ornamental design for a retractable top for a vehicle as shown and described.

DESCRIPTION

FIG. 1 is a side perspective view of a retractable top for a vehicle showing my design, the retractable top including a rigid outer portion and a foldable inner portion that is slidably movable relative to the rigid outer portion between an open position, as shown in FIG. 1, and a closed position, as shown in FIGS. 4 and 5.

FIG. 2 is a front perspective view of my design showing the foldable inner portion in a position that is between the open position and the closed position.

FIG. 3 is a rear perspective view of my design showing the foldable inner portion in a position that is between the open position and the closed position.

FIG. 4 is a side perspective view of my design showing the foldable inner portion in the closed position; and,

FIG. 5 is a rear perspective view of my design showing the foldable inner portion in the closed position.

My design extends to—but does not include—the dash-dot boundary line at the periphery of the rigid outer portion.

The dashed lines in the figures form no part of the claimed design. Surface shading in the figures indicates contour, and stippling in the figures indicates contrast—whether in color and/or finish—between the rigid outer portion and the foldable inner portion. Any surfaces or portions of my retractable top for a vehicle not shown in the figures or otherwise described in the specification form no part of the claimed design.
